UNITED STATES PATENT OFFICE.

JAMES EVELETH MAYNADIER, OF TAUNTON, MASSACHUSETTS.

TELpherage SYSTEM.

SPECIFICATION forming part of Letters Patent No. 441,250, dated November 25, 1890.

Application filed August 4, 1890. Serial No. 360,982. (No model.)

To all whom it may concern:

Be it known that I, JAMES EVELETH MAY-

NADIER, of Taunton, in the county of Bristol
and State of Massachusetts, have invented an
Improved Telpherage System, of which the
following is a specification, reference being
had to the accompanying drawings, making
a part hereof, in which—

Figure 1 is a side elevation showing the cap
and one section of a compound vehicle em-
bodying my invention. Fig. 2 is a front ele-
vation of Fig. 1 with the cap removed. Figs.
3 and 4 are sections on lines 3 3 and 4 4 of
Fig. 1. Figs. 5, 6, and 7 are sections on lines
5 5, 6 6, and 7 7 of Fig. 3. Fig. 8 is a side
elevation, partly in section, of one form of
cap. Fig. 9 is a sectional elevation of a track-
coil and tracks with the vehicle in dotted
lines. Fig. 10 is a double view, the right half
being a section on line 10 10 of Fig. 9, and
the left half a section on line 10^a 10^a of Fig.
9. Fig. 11 is a diagram illustrating a com-
pound vehicle with ten (10) coils in connec-
tion with five (5) track-coils.

In my patent, No. 425,038, dated April 8,
1890, I have described a system of telpher-
age now called the "teleport," which consists,
essentially, of a vehicle propelled by means
of alternating currents through a number of
stationary coils or rings; and my present in-
vention relates, primarily, to vehicles for the
teleport system, and consists in a compound
vehicle made up of a number of coils con-
nected together to form a single vehicle by
means of hollow couplings.

Another feature of my invention relates to
the construction of the track-coils or con-
ductors, and consists in a skeleton construc-
tion of the track-coils, as fully explained be-
low.

In the drawings, A A', &c., represent ve-
hicles each composed mainly of a coil sub-
stantially such as are described in my patent
above referred to.

B B', &c., represent hollow couplings. The
front and rear coils A and A' are provided
with caps C C' of the proper shape to aid in
reducing air-resistance when the compound
vehicle travels rapidly through the air. I
prefer to make these caps detachable for ease

in emptying and filling the compound ve-
hicle.

The coils or cars A A', &c., are substantially
as described in my patent, except that they
are provided with a suitable fastening to re-
ceive the studs b², which project from the
couplings B B', &c. I have shown each com-
pound vehicle as made up of a number of
coils A A', &c., each permanently secured to
couplings B B', &c., for convenience in emp-
tying and filling; and also, in order that any
car A A', &c., may be readily replaced by an-
other, I prefer to make the cars A A', &c., and
couplings B B', &c., uniform, respectively,
and connect them by fastenings, so that they
can be readily attached. The fastening shown,
consisting of three studs b³ on each coupling,
which enter corresponding holes in the head
a and are there caught by a catch a², is a sim-
ple and efficient fastening.

The main advantage of my invention is
that it allows the track-coils to be placed far-
ther apart than is possible where the car is
constructed as shown in my patent without
loss of effective pull or propelling force, and
where very high speeds are required ena-
bles the pull or propelling force to be many
times increased. Thus, if one car A were used
singly it would be subjected to a given pull
every time it passed through a coil; but my
compound car is subjected to ten such pulls
when ten cars A A', &c., are coupled together to
form one compound car—that is, the pull is
increased ten times with the same number of
track-coils or five times with half the num-
ber, or is the same with one-tenth the num-
ber. The couplings being hollow increase
the holding capacity of the compound ve-
hicle, and the convenience for loading and
unloading is much greater when the com-
pound vehicle is so constructed that it can
readily be divided into sections light enough
to be easily handled and open at each end.
The couplings being composed mainly of steel
spiral springs, also give the flexibility desir-
able for curves in the track, whether vertical
or horizontal.

The couplings are best formed of spiral
springs which are covered with a leather or
other stout covering. I have shown three

spiral springs whose axes coincide in each coupling, all three of which are secured at one end to a car-section and at the other end to a ring, from which the studs b^3 project.

5 These three spiral springs and their covering thus make a short cylinder, which, in connection with the car A, constitutes a car-section, a number of these sections connected making the compound car, and by means of the studs b^3 the coupling fast to car A is readily connected to the head a of the car A', as above explained.

In the diagram Fig. 11, I illustrate a vehicle long enough to be acted upon by several track-coils D D', &c., simultaneously. Here the vehicle is first propelled by the energy of coil D acting with the coil on car A, next of coil D acting with coil of car A', and so on, until all the car-coils act in connection with 15 coil D, but, as will be clear from the diagram, coils D D', &c., will all act when arranged relatively to the car, as shown in Fig. 11, with each of the car-coils. I reduce the air-resistance by allowing the ready escape of air from 20 the track-coils; and this part of my invention consists in leaving air-spaces between the turns of the track-coil and in supporting the track-coils upon a skeleton support—that is, 25 a support with air-spaces—as shown in Figs. 30 9 and 10.

The details of construction shown may be widely departed from, as I have shown only the preferred form; but the main matter is to allow the free escape of air from the track- 35 coils, which I accomplish by the spaces between the convolutions d of the coils and the spaces between the parts of the frame d' , by which the coils are held.

In the plan shown the circuit from the 40 mains L L' is completed through each car-coil as soon as it becomes flush with a track-coil by means of the brushes f and electrodes f' on the vehicle, and as the track-coil is a closed circuit a current is induced in it, and 45 the car-coil is subjected to a force tending to move it endwise through the track-coil, as well as to center it in the track-coil. Suppose now that the number of convolutions or turns in each car-coil is, say, for easy figuring, one 50 hundred, that the leads L L' are kept at a constant difference of alternating potential of, say, one thousand volts, and that the leads are large enough to carry a current of, say, one hundred ampères; also, that it is desired 55 to have a maximum current of one hundred ampères at one thousand volts in the car-coil. Then, as it is highly desirable to reduce the amount of wire in each track-coil to the minimum, and as the track-coils may be regarded 60 as secondary conductors, the car-coils being the primary, it will be necessary to determine the current which must flow through the track-coil in order that a current of one hundred ampères at one thousand volts may flow 65 through the car-coil. If the number of turns in the track-coil were equal to the number in the car-coil, the voltage would be the same

substantially in both coils, and the resistance in the track-coils would therefore be made sufficient to prevent more than the maximum 70 current of one hundred ampères flowing through it with a voltage of one thousand; but this would require a very fine wire in order to get ten ohms resistance. I therefore prefer to reduce the voltage by reducing 75 the number of turns in the track-coils; but this of course requires a larger current in the track-coils. For example, if there be but twenty turns in each track-coil and one hundred turns in each car-coil—that is, five times 80 as many turns in the car-coil as in the track-coil—the maximum voltage of the current induced in the track-coil will be twenty one-hundredths or one-fifth of the voltage in the car-coil, or two hundred volts in the track- 85 coil with one thousand volts in the car-coil. On the other hand, the maximum current in the track-coil must be five times that of the maximum current in the car-coil, or five hundred ampères if one hundred ampères be desired in the car-coils. The ohmic resistance 90 in the track-coil must therefore be only four-tenths of an ohm, which allows a wire to be used for the track-coils of a cross-section so large that it is readily fastened to its skeleton 95 support, as shown in the drawings. Such a wire would of course be heated far more than it should be if the induced current were continued for an appreciable time; but the induced current in any track-coil lasts only a 100 small fraction of a second, and for that reason the heating effect may be practically disregarded—that is to say, the cross-section of the wire may be far smaller than would be practical if the maximum current in the track- 105 coils were to flow without interruption for a considerable time.

It will be obvious that a soft-iron core may be dispensed with in the car; but for greater effect I use a soft-iron core on the track-coils, 110 and this core must be a skeleton to allow the free escape of air radially from the track-coils. The core shown is made of bundles d' of strips of sheet-iron, the bundles being arranged in a circle and held by rings d^3 at 115 each end, or otherwise properly secured to the heads d^4 of the track-coils.

While I have shown my compound vehicle as made up of a number of pairs, each consisting of a car and coupling, that is mainly 120 for the purpose of ready separation into parts, for, as will be clear, the vehicle may be a long tube of rubber or leather somewhat like a suction-hose, with a spiral of copper wire reaching from end to end, the brushes 125 being so arranged as to cause a current (either from the mains or induced) through a portion only of the spiral at any one moment. In this case that part of the coil which is made a closed circuit by the brushes corresponds with the coils of that form of my improved vehicle shown in the drawings, while that part of the car surrounded by those turns of the coil which are not energized is 130

the coupling during that time. This compound vehicle although in one sense it is a single car is yet in substance my compound vehicle, for the coil is divided up by the 5 brushes into a series of coils acting one after the other with the track-coils, and at any given moment the active turns of the coil are connected by the idle turns, which then form with the leather tube hollow couplings.

10. What I claim as my invention is—

1. The compound vehicle above described, consisting of a plurality of coils A A', &c.,

connected by hollow couplings B B', &c., and provided with terminal caps C C', all substantially as set forth.

2. The skeleton track-coils above described, whose turns d have air-spaces between them, and whose support d' is also provided with air-spaces, all substantially as described.

JAMES EVELETH MAYNADIER.
